(57) CLAIM

The ornamental design for a multi-panel edgelit luminaire, as shown and described.

DESCRIPTION

FIG. 1 is a top perspective view of a multi-panel edgelit luminaire, showing my new design;

FIG. 2 is a bottom perspective view thereof;

FIG. 3 is a top plan view thereof;

FIG. 4 is a bottom plan view thereof;

FIG. 5 is a left-side elevation view thereof;

FIG. 6 is a right-side elevation view thereof;

FIG. 7 is a front elevation view thereof; and,

FIG. 8 is a rear elevation view thereof.

The broken lines shown represent portions of the multi-panel edgelit luminaire that form no part of the claimed design. The area between the curved broken lines shown passing through the design forms no part of the claimed design.
